Attorney.

UNITED STATES PATENT OFFICE.

EDGAR E. GREVE, OF BELLEVUE, PENNSYLVANIA.

CASING ELEVATOR.

Application filed September 27, 1923 Serial No. 665,093.

This invention relates to an elevator for manipulating well casings in the operation of earth boring.

The invention relates generally to the type 5 of elevator shown in my prior United States Letters Patent No. 1,180,031 of April 18, 1916, in which there is a main body on which are two pivoted doors.

The present invention relates particularly 10 to an improved latching means for holding the doors closed, which latching means is particularly suited for an apparatus of this kind wherein a high safety factor must be combined with facility of operation, so that 15 sections of casing or drill pipe, in rotary drilling operations, may be safely but easily and rapidly handled.

The invention may be readily understood 20 by reference to the accompanying drawings, 20 in which:

Fig. 1 is a top plan view of an elevator embodying my invention; and

Fig. 2 is a side view thereof.

In the drawings, 5 designates the main 25 body of the elevator. On the body 5 at diametrically opposite points, are trunnions 6 to which a bail, not shown, is attached, for suspending the elevator in the usual manner.

30 At 6^a are pivots or hinges for the doors 7 and 8. On the door 7 are two bosses designated 9 to which a fixed handle 10 is secured. On the free edge of door 7, between the lugs or bosses 9, is a hook-like projection 11, the nose 12 of the hook portion of which is turned away from the door 8, and is rounded, as shown in Fig. 1.

On the door 8 are two bosses or ears 13 in which is rotatably carried a shaft 14 having an eccentric cam 15 secured thereto, this cam being secured to that portion of the shaft between the two lugs. The ends of the shaft project beyond the lugs, and secured to these ends and fast thereto, are the ends of 45 a handle 16.

The eccentric 15 is fitted in and passed through the inner end portion of a locking member 17. This locking member has a hook 17^a on its outer end for cooperation 50 with hook 11. On the locking member is a hook-like abutment 18, against which spring 19 re-acts, this spring being looped around shaft 14 and being confined by a rib 20 on the door 8. The locking member also 55 has lugs 21 thereon which engage against door 8 when the hook is in the latching

position of Fig. 1, whereby the hook is prevented from ever swinging in beyond the position shown. This is important because, when the doors are opened, the spring would tend to urge the latch around so that it would otherwise swing too far inwardly and be in the way.

In use, the elevator, when the doors are closed, engages the casing or drill pipe, 60 shown in section in Fig. 1 and designated A, in the usual manner. The hook 17^a engages with hook 11 to hold the doors against opening, and the spring 19 tends to hold the parts in this position. Movable handle 16 65 is then nearly, but not quite, parallel with fixed handle 10. To open the doors, handle 16 is moved in an arc in the direction of the arrow of Fig. 1. This rotates shaft 14 and eccentric 15, to reciprocate member 17 70 until hook 17^a is disengaged from under the nose 12 of hook 11. Then, by pulling on both handles, the doors may be fully opened.

As soon as handle 16 is released, spring 75 19 urges member 17 into locking position, even though the doors be opened. Consequently, to lock the doors, it is only necessary to move them into closed position. Hook 17 riding on rounded nose 12 of hook 80 11 will slide thereon, and so is easily moved into locking position.

When the doors are locked, the doors can only be opened by moving handle 16 away from handle 10. Consequently, any obstruction 85 which the elevator might engage in operation must be of a nature that would apply a pressure between the handles before the doors would open, and such obstruction is not likely to be encountered in a manner to open the doors. The arrangement of a 90 reciprocable latch not only provides an elevator which is substantially proof against accidental opening, but also provides a structure wherein the doors may be drawn together into a tight gripping relation with 95 a section of pipe or casing after the doors have been closed, and this can be done with considerable ease.

Various changes and modifications may be 100 made in the invention within the contemplation of my invention and under the scope of the appended claims.

I claim as my invention:

1. A casing elevator having a door, a 110 latch pivotally and reciprocably mounted on the door, means for reciprocating the latch into and out of locking position including

an eccentric secured to the latch and a handle for moving the eccentric, and a hook with which the latch cooperates.

2. A casing elevator having a door, a latch pivotally and reciprocably mounted on the door, means for reciprocating the latch into and out of locking position including a shaft having an eccentric and a handle mounted thereon, means for preventing the latch from swinging inwardly past an operative position, and a hook with which the latch cooperates.

3. A casing elevator having a door, a latch pivotally and reciprocably mounted on the door, means for moving the latch into and out of operative engagement including a shaft carried by the door, an eccentric connecting the latch and the shaft, and a handle secured to the shaft.

20 4. A casing elevator having a door, a latch pivotally and reciprocably mounted on the door, means for reciprocating the latch into and out of locking position including a shaft having an eccentric and a handle mounted thereon, a spring for resiliently urging the latch to and holding it in locking position, means for preventing the latch from swinging inwardly out of an operating position, and a hook with which the latch cooperates.

35 5. A casing elevator having a door, a latch pivotally and reciprocably mounted on the door, means for reciprocating the latch into and out of locking position including a handle, an abutment on the latch, an abutment on the door, and a spring confined between said abutments for resiliently urging the latch into latching position, and a hook with which the latch cooperates.

40 6. A casing elevator comprising a body, a pair of doors on the body, a longitudinally extending fixed handle on one door, a fixed latch engaging member on the same door, a latch on the second door, a longitudinally extending movable handle on the second door operatively connected with the latch, the two handles being relatively close together when the doors are latched, said latch operating handle being movable away from the fixed handle to release the latch, said fixed handle thus forming a guard for the movable one.

55 7. A casing elevator comprising a body, a pair of doors on the body, a hook having a rounded nose portion on one door, a latch on the other door having a hook adapted to

slide over the nose of the first hook and for cooperation with said first hook, said latch being pivotally and slidably mounted on the door, a spring for urging the latch to locking position, and an operating mechanism for the latch including a shaft, an eccentric connecting the latch and the shaft, and a handle on the shaft.

8. A casing elevator comprising a body, a pair of doors on the body, a hook having a rounded nose portion on one door, a latch on the other door having a hook adapted to slide over the nose of the first hook and for cooperation with said first hook, said latch being pivotally and slidably mounted on the door, a spring for urging the latch to locking position, an operating mechanism for the latch, and means on the latch for holding it from swinging inwardly past hook engaging position.

9. A casing elevator including a body having two hinged doors thereon, a fixed handle on one door, a latch engaging member on the same door, spaced apart lugs on the other door, a shaft journaled in the lugs, an eccentric on the shaft, a latch member rotatably carried on the eccentric and adapted to be reciprocated thereby, and a handle fixed on the shaft for moving the eccentric.

10. A casing elevator including a body having two hinged doors thereon, a fixed handle on one door, a latch engaging member on the same door, spaced apart lugs on the other door, a shaft journaled in the lugs, an eccentric on the shaft, a latch member rotatably carried on the eccentric and adapted to be reciprocated thereby, a handle fixed on the shaft for moving the eccentric, and a spring on the shaft engaging the latch and engaging the door for urging the latch to latching position.

11. A casing elevator including a body having two hinged doors thereon, a fixed handle on the first door, a latch engaging member on the same door, spaced apart lugs on the second door, a shaft journaled in the lugs, an eccentric on the shaft, a latch member rotatably carried on the eccentric and adapted to be reciprocated thereby, a handle fixed on the shaft for moving the eccentric, and a lug on the latch for engagement with the second door for keeping the latch from swinging inwardly past operative position.

In testimony whereof I affix my signature.

EDGAR E. GREVE.
